UNITED STATES PATENT OFFICE.

ALBERT J. RENARD, OF ST. PAUL, MINNESOTA.

CARBURETOR.

Application filed September 18, 1925. Serial No. 57,200.

The present invention relates to a carburetor for internal combustion motors.

It is common practice in feeding gasoline, or other liquid fuel to the cylinders of an internal combustion motor, to draw a current of air over an open jet of the fuel to thereby force the air to pick up the fuel from the jet and carry it into the cylinders in the form of an explosive mixture with the air.

When gasoline is thus drawn from a jet by means of a rapidly passing current of air, a large portion of the gasoline is vaporized, but some may remain in the form of small drops, and these, upon striking the walls of the intake manifold of the motor, adhere to said walls and may be drawn into the cylinders in the form of a liquid rather than in the form of a gas. It is well known that gasoline in a liquid form is not an explosive substance, but acquires an explosive quality upon being mixed with a definite quantity of air. Various expedients have been employed to prevent drops of gasoline from condensing out of the mixture after gasoline has been mixed with air by being drawn through a carburetor, but most of these expedients are aimed at revaporizing the liquid after condensation.

An object of the present invention is to draw gasoline in liquid form from a jet, mix it with a small quantity of air, and superheat the mixture of gasoline and air and to then pass said mixture through a device where a sufficient quantity of air will be added to make an explosive vapor thereof.

Another object is to mix gasoline and air in non-explosive proportions, heat the non-explosive mixture thus formed, and pass said non-explosive mixture through a device where a sufficient quantity of air is added to the mixture to make an explosive mixture thereof.

In order to attain these objects, there is provided, in accordance with one feature of the invention, a float chamber of an ordinary type, having a well connected thereto with the top of the well slightly above the normal level of gasoline in the float chamber. A needle valve is operatively mounted in the well to regulate the flow of gas through the well. A housing surrounds the well and is provided with a perforation laterally adjacent the top of the well. A tube is connected to the housing and passes into

the exhaust manifold of the motor. The tube is then led from the exhaust manifold to a Venturi throat in open communication with the intake manifold of the motor. A spring controlled air intake valve is operatively mounted to control the amount of air passing through the venturi, and a control valve is operatively mounted on the motor side of the venturi to control the flow of the gas mixture through the device.

These and other features of the invention, not specifically mentioned, will be more fully brought out in the following description and the accompanying drawings, wherein:

Figure 1 is a view in side elevation, partly in section, of a carburetor made in accordance with the present invention, the intake and exhaust manifolds of a motor being shown therewith.

Figure 2 is a view in enlarged vertical section of a gasoline well; and

Figure 3 is a view in enlarged top and side elevation respectively of a spring controlled air valve.

Referring to the drawings in detail, an intake manifold 1 and an exhaust manifold 2 are represented in the positions which they occupy when operatively mounted upon one type of automobile motor. Connected to the lower end of the intake manifold 1 by means of bolts 3 is a mixing chamber A having a Venturi throat 4 affixed therein. The venturi is provided with a peripheral groove 5 having a plurality of air inlet ports 6 extending therefrom to the interior of the Venturi throat.

A hole 7 is drilled in the wall of the mixing chamber A to communicate with the groove 5, and into this hole is threaded a tube 8. The tube 8 passes upward and through the wall of the exhaust manifold at 2, thence interiorly of the exhaust manifold to the point 9, whence it again emerges from the exhaust manifold and passes downwardly and is connected to a mixing well B. The mixing chamber A is provided with a top 10 connected to the body of the mixing chamber to form an air-tight joint therewith. A rod 11 is threaded in the top of the chamber A and is provided with a knurled top 12 by means of which the rod may be rotated to change its vertical position in the chamber, and a lock nut 13 by which the rod 11 may be secured against rotation. A washer 14 is integrally connected to the rod 11.

110

11 after the rod is threadedly inserted in the top 10, and forms a stop to limit the upward movement of the rod, and also acts as a seat for the upper end of a coil spring 15. The lower end of the coil spring is connected to a valve 16, shown in detail in Figure 3, the central opening 17 of which is slidably mounted upon the rod 11, the outer edge of the valve seating upon a shoulder 18 formed around an opening 19 in the bottom of the valve chamber A. A plurality of perforations 20 are provided in the valve 16 to provide air inlet means when the motor is running at low speed, to thereby prevent the valve from chattering when a small quantity of air is being drawn therethrough. The spring tension holding the valve 16 on its seat may be increased by screwing the rod 11 downward to force the washer 14 downwardly against the top of the spring 15 to compress it, and may be decreased by the reverse of said operation.

A bracket 21 integral with the valve housing extends laterally therefrom and forms a support for a float chamber B. The float chamber is of a conventional type, having a valve 22 connected to a float 23. A gasoline feed pipe 24 of an ordinary type is connected to a gasoline supply tank, not shown. 25 In open communication with the interior of the float chamber is a laterally extending hollow arm 25 upon which is threadedly mounted a bottom closure member 26 of a feed well C. The detailed structure of the 30 feed well is shown in Figure 2.

In the feed well the bottom closure member 26 is integrally connected to a lower tubular member 27 having a band 28 integrally connected to the interior of the upper portion thereof, as by welding, the band 28 extending above the upper edge of lower tubular member 27 and being threaded to receive a tubular upper portion 29. Integrally connected to the interior of the upper tubular portion 29, is a housing 30 which extends downward into the lower tubular member to have close slidable contact over a feed pipe 31 which is threadedly inserted in the bottom closure member 26. The housing 30 is provided with a plurality of air inlet passages 32, located closely above the top of the feed pipe 31; and a vent 33 in the side of the lower tubular member 27 (see Figure 1) is provided to supply air to the inlets 32. 40 45 50 55 60

A top closure member 34 is threadedly connected to the top of upper tubular member 29 to have air tight connection therewith, and a needle valve 35 of conventional type is threadedly mounted centrally of the top closure member to regulate the flow of gasoline through the feed pipe.

An electrical heating coil 36 of a conventional type is positioned to surround the upwardly extending tube 8 at a point preferably closely adjacent the venturi 4 to pro-

vide means for heating the tube 8 when starting the motor in cold weather.

In operation, a partial vacuum is created in the intake manifold 1 by cranking the motor, and this in turn, through the tube 8, creates a partial vacuum in the upper portion of the intake well above the housing member 30. The float 23 is adjusted to maintain the gasoline level in the feed pipe 31 closely adjacent the top thereof, and when a partial vacuum is created in the upper portion of the feed well air is drawn through the opening 33 in the side of the lower tubular member 27 and passes through the inlet passages 32 into the housing 30. As the air passes through the inlet passages 32 it picks up a quantity of gasoline from the feed pipe 31 and conveys it in the form of a partial vapor through the tube 8 and thence to the openings 6 in the venturi 4. Simultaneously with the drawing of the partially formed vapor through the tube 8, a quantity of air is drawn past the valve 16 and through the venturi. As the air passes through the venturi it picks up the partially formed vapor, passing through the ports 6 and carries it into the cylinders of the motor where it is exploded by an electrical spark in a conventional manner.

In starting the motor in cold weather, the resistance coil 36 may be connected with a source of electrical current such as a storage battery, not shown, for a short period of time prior to starting the motor, approximately thirty seconds being sufficient in ordinary cases. This heats the partially formed vapor passing through the tube 8 and expedites its vaporization. After the motor has been operating for a short time, exhaust gases, passing through the manifold 2, heat the tube 8 to a high temperature and vaporize any liquid gasoline present in the tube 8. After the tube 8 becomes heated it is possible to use a fuel having a lower vaporization point than gasoline, such as kerosene, and when this is desired, a tank of kerosene having alternate connection with the feed pipe 24 may be connected thereto by means of a two-way cock, not shown, in a well known manner.

A choke valve 37 is provided in the air intake passage 19, and in starting the motor this valve is closed for a short period to heighten the vacuum in the tube 8 and thereby increase the flow of vapor through the tube 8.

What I claim is:

A carburetor for an internal combustion motor comprising a fuel well, a housing surrounding said fuel well, said housing being provided with perforations to admit a relatively small quantity of air into the interior of said housing when the pressure in the housing is reduced below atmospheric pressure, a Venturi throat in open communica-

tion with the intake manifold of the motor, a controlled air valve operatively associated with the Venturi throat, feed means connecting the interior of the housing surrounding the fuel well with the Venturi throat to conduct a vapor of gasoline and air from the housing surrounding the feed well to the

Venturi throat, said feed means being positioned with respect to the exhaust manifold of the motor to heat the vapor and prevent 10 condensation of liquid gasoline therefrom.

In testimony whereof I affix my signature.

ALBERT J. RENARD.
